UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

DRAWER-LOCKING MECHANISM FOR TRUNKS.

1,374,383.

Specification of Letters Patent. Patented Apr. 12, 1921.

Application filed September 14, 1918. Serial No. 254,027.

To all whom it may concern:

Be it known that I, FRANK W. MEYER, a citizen of the United States, residing at Oshkosh, in the county of Winnebago and 5 State of Wisconsin, have invented new and useful Improvements in Drawer-Locking Mechanism for Trunks, of which the following is a specification.

This invention relates to a drawer locking 10 mechanism for trunks whereby a tier of drawers in the drawer section of a wardrobe or like trunk may be locked and unlocked simultaneously through the manipulation of a single element of such mechanism, accessible from the outside of said drawer section when the trunk is open.

Among the objects of my invention is to 15 improve the construction of a drawer locking mechanism of the kind referred to, in the several particulars as will hereinafter more fully appear, and to provide in particular a drawer locking mechanism which may be operated by the same key which is used to unlock the lock on the outside of 20 the trunk. A further object of my invention is to provide an improved form of locking member on the invertible drawer of the hat drawer construction, so as to avoid the use of any supplemental parts on the locking 25 bar for the invertible drawer.

The invention consists further in the matters hereinafter described and more particularly pointed out in the appended claims.

In the accompanying drawings:

35 Figure 1 is an elevational view of a wardrobe trunk, and showing the two hinged together upright sections thereof unlocked and swung apart into open position, with the drawer section of said trunk equipped with 40 a drawer locking mechanism embodying the features of my invention;

Fig. 2 is a vertical sectional view taken through the drawer section of said trunk on line 2—2 of Fig. 1;

45 Fig. 3 is a horizontal sectional view, with parts in elevation, taken on line 4—4 of Fig. 2;

Fig. 4 is an enlarged vertical sectional view, with parts in elevation, taken through 50 the part of the trunk in which the key operable lock of my drawer locking mechanism is located;

Fig. 5 is a rear elevational view of said lock, the same being shown removed from 55 the trunk for the purposes of illustration;

Fig. 6 is a view of that end of the actuating rod which connects with the rotatably mounted cylinder shown in Figs. 4 and 5;

Fig. 7 is a rear elevational view of the tier of drawers in the drawer section of the 60 trunk, some of the associated parts of the trunk construction being omitted for the sake of clearness of illustration;

Fig. 8 is a vertical sectional view taken on line 8—8 of Fig. 2;

Fig. 9 is a perspective view of the rear end portion of said actuating rod, and illustrating the associated parts disassembled but in position to be engaged with each other in their proper order;

Figs. 10 and 11 are perspective views, respectively, of the locking members provided on the rear walls of the drawers; and

Fig. 12 is a side elevational view of the key used to unlock the lock on the outside of 75 the trunk as well as to actuate the drawer locking mechanism of my invention.

The trunk 1, shown in the drawings, is of the wardrobe type and comprising two hinged together, upright sections 2 and 3, 80 the former being the wardrobe section and the latter the drawer section of said trunk. Among the customary appurtenances located in the wardrobe section 2 is a pair of extensible trolleys 4, 4, upon which are hung the garment hangers 4^a, as shown in Fig. 2. When the sections 2 and 3 are swung together into closed position, they may be locked together on the outside thereof by a lock 5 secured to the section 2 and having a hinged 90 hasp 6 adapted to be swung into and out of locking engagement with a socketed type of keeper 7 provided on the outside of the section 3, as shown in Fig. 1. Said trunk 1 is equipped with that type of trunk locking 95 mechanism as shown in Reissue Letters Patent No. 14,143, granted to me on May 30th, 1916, and in such construction the lock 5 forms the outside member thereof and by means of which the inside locking members 100 are actuated. It is to be understood, however, that I may use a trunk lock of any other type without departing from the spirit and scope of my present invention, it being preferable, however, that the same key which is used for unlocking the outside trunk lock may also be used for actuating the drawer locking mechanism of my present invention.

As shown in Fig. 1, the hasp 6 is provided at its swinging end with a key operable 110

lock, preferably of the type having a rotatably mounted cylinder or like part 8 adapted to be rotated into unlocked position by a key 9 (Fig. 12) when the latter is inserted in the key-hole provided in said cylinder.

The drawer section 3 has two upright side walls 10, 10, a bottom wall 11, a top wall 12, and an upright back or rear wall 13, all of which are connected together and form a compartment to receive a tier of drawers 14 to 18, inclusive. Said drawers are mounted in said section 3 so that they may be readily moved into open and closed positions when unlocked and the trunk open. In the trunk illustrated, said drawers are slidably mounted one above the other and with the uppermost drawer 14 resting on a horizontally arranged, flat, partition wall 19 secured in said drawer section. As shown in Fig. 2, the drawer 16 rests on a like partition wall 20, also secured in said drawer section. The drawers 15 and 17 each rest and slide on L-shaped metal strips 21, 21 secured to the side walls 10, 10 for that purpose. The bottom drawer 18 rests on the bottom wall 11 of the drawer section 3.

For simultaneously locking and unlocking all of the drawers 14 to 18, inclusive, through the manual manipulation of one of the elements of a drawer locking mechanism, I provide the following construction. Located in the drawer section 3 and to the rear of the drawers is a locking bar 22 vertically arranged and extending substantially the full height of said drawer section 3. Said bar 22 is made flat and relatively narrow, and has a length to extend across the rear walls 14^a to 18^a, inclusive, of said drawers, as shown in Figs. 2 and 8. The upper end of said bar 22 is connected by a pivot pin 23 with the outer or swinging end of a link 24, while the lower end of said bar 22 is connected by a pivot pin 25 with the like end 45 of a link 26. Said link 26 is connected by a pivot pin 27 with the rear wall 13 of said section 3. Secured to said rear wall 13 at the upper end of said bar 22 is a flat plate 28 provided between its ends with an outwardly opening circular hole or socket 29 (Figs. 2 and 9). Extending outward from the rear wall 13 and above the uppermost drawer 14 is an actuating rod 30. Said rod 30 passes loosely through a hole 31 at 50 one end of said link 24, and the inner end of said rod 30 is rotatably received in the socket 29 in said plate 28. Said link 24 being loosely mounted on said rod 30, it follows that the latter may be rotated relatively to 55 said link. Said links 24, 26 support said bar 22 and enable the same to be moved endwise and laterally when moved into and out of locking position. The opposite or outer end of said rod 30 is secured to the cylinder 32 of a tumbler type of lock 33, re-

tained in a front wall 34 extending between the side walls 10, 10 of the drawer section 3 and downward from the top wall 12 thereof. That portion of the rod 30 adjacent the lock 33 extends through and is rotatably mounted in a supporting strip 35 depending from the top wall 12 back of said front wall 34. Said wall 34 and strip 35 may be made in one piece if desired. To prevent the articles placed in the top drawer 14 from contacting with the rod 30, I provide a partition wall 36 between said rod and the top of said drawer 14. For connecting the rod 30 with the uppermost link 24 so that movement may be imparted from said rod to the bar 22 for locking and unlocking all of the drawers 14 to 18 simultaneously, the rod 30 is provided with a radially projecting pin 37 adapted in the rotation of said rod 30 to be brought into contact with a lug 38 made rigid with and extending outward from one side of said link 24, as shown in Figs. 2, 8, and 9. The lug 38 being in the path of movement of said pin 37, it follows that when the rod 30 is rotated in one direction, the link 24 will be swung upward to raise the bar 22, and when rotated in the opposite direction will strike the lug on the other side thereof and swing the link 24 and the bar 22 downward for locking the drawers. Each drawer 14, 15, 16, and 18 is provided on its rear wall with a rearwardly extending locking member 39, which is made from a strip of sheet metal bent to have the shape as shown in Fig. 10. As shown, said locking member 39 has a flat body portion 40 adapted to be secured flatwise against the back or rear wall of the drawer and an outwardly offset portion 41 forming a hook to engage over the bar 22 from one side thereof when the latter is moved into locking position, as shown in dotted lines in Fig. 8.

The drawer 17 is provided with a bottom wall 42 connected by a hinge strip 43 with the inside face of the rear wall 17^a of said drawer, as shown in Fig. 2. When the drawer 17 is in the inverted position shown in said figure, the bottom wall 42 extends downward in the drawer 18 along the rear walls of said drawers, and is detachably received in sockets formed by members 44 secured to the side walls of said drawer 18. This connects the drawers 17 and 18 together at the rear, while a padded hat retainer 45 connects said drawers together at their front walls, there being loop shaped members 46, 46 secured to said drawers on the inside thereof and engaged by a metal strap 47 on the back of said hat holder 45. When the hat holder 45 is removed, the drawer 17 may be inverted so that the hinged wall 42 will drop into a position resting on the stop strip 48 and form the bottom wall of said drawer, whereupon the drawers 17 and 18 are dis-

connected and may be used as separate drawers. Such invertible drawer construction forms the subject-matter of my prior Patent No. 1,121,933, granted December 22nd, 5 1914, and has only been illustrated herein in order to show the particular type of locking member 49 which I use with my improved drawer locking mechanism herein shown and described. As best shown in Fig. 11, said 10 locking member 49 is made from a flat piece of metal and has a body portion 50 adapted to be inserted through the rear wall 17^a of said invertible drawer 17. Said body portion 50 has prongs 51, 51 designed to project slightly into the inside of said drawer 17 and there to be upset for securing said locking member 49 to said invertible drawer 17. At the opposite end of said member 49 are two lugs 52, 52 extending at right angles to said body portion and projecting laterally therefrom on opposite sides thereof. By this arrangement, it follows that one 15 of said lugs 52 always is in a position to extend over said bar 22 from one side thereof in either of the two positions of said drawer 17, as shown by noting Figs. 7 and 8. It is by reason of such member 49 that the bar 22 need not be provided with any supplemental locking parts to engage said member in 20 either of the two positions of said invertible drawer 17.

As clearly shown in Figs. 2 and 3, each 25 partition wall 19, 20 is provided in its rear edge with a cut out portion 53, through which said bar 22 extends. Secured to each 30 partition wall 19, 20 and extending over the recess 53 therein is a metal plate 54 provided with an elongated slot 55 having a length sufficient to permit the bar 22 to be moved 35 from locking to unlocking position. Said bar 22 may contact with one end of said slot 55 when moved into locking position, so as to prevent said bar from striking the locking members 39, 49 on the drawers, although 40 any other type of stop member may be provided for that purpose. Each drawer is 45 provided on its front wall with a handle 56.

Assume that the trunk 1 is closed and 50 locked and that the drawers 14 to 18 are all locked by my improved drawer locking mechanism: The outside lock 5 is unlocked by the key 9 and the trunk opened by swinging or moving the sections 2 and 3 apart. Then the same key 9 is inserted into the key- 55 hole in the cylinder 32 of the drawer lock 33. The key 9 is then turned to rotate the rod 30 in a direction to cause its pin 37 to be brought into contact with the under side of the lug 38, as shown in Fig. 8, whereupon a 60 continued rotation of the key will swing the link 24 upward from the position shown in dotted lines in said Fig. 8 to the position shown in full lines in said figure, with the result that the bar 22 will be raised and 65 swung obliquely outward from behind the

locking members 39 and 49 at the rear of the drawers 14 to 18, as shown in said Fig. 8. When the parts have been moved to such positions, all of the drawers are simultaneously unlocked and either one or all may be 70 opened and closed as desired. To lock the drawers simultaneously, the drawers are all closed, whereupon the same key 9 is engaged with the cylinder 32 and turned in the opposite direction, thereby rotating the rod 30 75 until the pin 37 strikes the opposite or upper side of the lug 38. A continued turning of said key 9 causes the link 24 to be swung downward from the full line position shown in Fig. 8 to the dotted line position shown 80 in the same figure, thereby causing the bar 22 to be moved obliquely downward to engage behind the locking members 39 and 49, as is apparent.

By providing a drawer locking mechanism which may be operated by the same key that is used for unlocking the trunk, it follows that the user or owner of the trunk is required to carry but one key for both the trunk and the drawer lock, instead of 85 two different keys for such locks, as is made necessary in the form of drawer locking mechanism as shown in my prior Patent No. 1,264,321, granted April 30th, 1918. The fact that the link 24 is loosely mounted on 90 the rod 30 permits rotation of the rod relatively to said link and thereby enables the pin and lug type of connection to be used between the rod and link, with the result that the leverage required to move the bar 22 upward is sufficient with the ordinary size of key that is used with the trunk lock 95 5. The downward movement of the bar is aided by gravity, and thus just sufficient leverage is required to start the bar 22 on 100 its downward movement. Other and further advantages incident to my invention 105 will be apparent to those skilled in the art to which my invention relates.

In order to prevent the drawers from 110 striking the bar 22, when said drawers are moved into fully closed position, I provide stop strips 57 secured to the rear wall 13 at the back of said drawers, as shown in Fig. 3. In the construction shown in the drawings, 115 the rod 30 is connected with the cylinder 32 by providing the inner end of the latter with a transverse slot 58 to receive a flattened integral lug or projection 59 on the adjacent end of said rod, as shown in Figs. 120 4, 5, and 6.

While I have shown and described herein one form of drawer locking mechanism constructed in accordance with my invention, it is of course understood that the various details of construction and arrangement of parts shown may be variously changed and modified without departing from the spirit and scope of my invention, and I do not wish to be limited to the details of construc- 125 130

tion and arrangement of parts shown, except as pointed out in the appended claims.

I claim as my invention:

1. In a trunk having a section containing 5 drawers, a locking bar located to the rear of said drawers and adapted to be moved into and out of locking engagement with locking members on said drawers, a rotatable rod for moving said bar, and means includ- 10 ing a lost motion construction connecting said rod with said bar.
2. In a trunk having a section containing 15 drawers, a locking bar located to the rear of said drawers and adapted to be moved into and out of locking engagement with locking members on said drawers, a rotatable rod for moving said bar, a key operable lock in said drawer section and having a rotatable member connected with said rod, and 20 means including a lost motion construction connecting said rod with said bar whereby the latter may be moved in the turning of said rod by the key of said lock.
3. In a trunk having a section containing 25 drawers, a locking bar located to the rear of said drawers and adapted to be moved end- wise and laterally into and out of locking engagement with locking members on said drawers, a rotatable rod for moving said 30 bar, a link loosely mounted on said rod and having pivotal connection with said bar, and said rod having an outwardly projecting pin adapted to be brought into contact with a lug on said link for moving said bar.
- 35 4. In a trunk having a section containing drawers, one above the other, a vertical lock-

ing bar to the rear of said drawers, a link at each end of said bar and pivotally connected therewith, the lower link being pivoted to the rear wall of said trunk section, a rotatable rod located above the uppermost drawer and having the upper link loosely connected therewith, said rod being provided with an outwardly projecting pin adapted to be brought into contact with a 45 lug on the upper link, and a key operable lock secured to a fixed part of the trunk section at the outer end of said rod and having a rotatable cylinder connected with said rod so that when a key is engaged with said 50 cylinder the rod may be turned for moving said bar.

5. In a trunk having a section containing sliding drawers, one above the other, a locking bar located to the rear of said drawers 55 and adapted to be moved into and out of locking engagement with locking members secured to said drawers, one of said drawers being invertible and the locking member at the rear thereof being provided with two 60 parts extending in opposite directions so as to engage over said bar from one side thereof in either position of said drawer.

In testimony that I claim the foregoing as my invention, I affix my signature in the 65 presence of two witnesses, this 9th day of September, A. D. 1918.

FRANK W. MEYER.
